ABSTRACT

An exponent indicating system for use in the display of an electronic calculator or the like, which comprises a decimal point register having memory places in excess of the effective indication or calculation places of the display. Using the excessive places, an exponent is indicated so as to show the approximate figures of a number having more places than the effective indication or calculation places.

EXPONENT INDICATING SYSTEM

BACKGROUND OF THE INVENTION

1. Field of the Invention

The present invention relates to an indicating system for an electronic calculator, etc., and more particularly to an exponent indicating system therefor.

2. Description of the Prior Art

In the conventional electronic desk calculators, when a calculated result or a set number exceeds the number of effective indication places or the number of effective calculation places, it is indicated as an error or overflow. This is a very undesirable condition.

SUMMARY OF THE INVENTION

The present invention has been made with a view toward improving the situation of the prior art, and has its object in making it possible to indicate the approximate figures of a number whose number of places is larger than the number of effective indication places or effective calculation places.

In accordance with the present invention, there is provided an exponent indicating system which comprises a decimal point register storing the position of the decimal point of a calculated result or a set number, an exponent being indicated in conformity with the contents of the decimal point register when they reach a predetermined value.

BRIEF DESCRIPTION OF THE DRAWINGS

FIG. 1a is a schematic block diagram of one embodiment of the present invention;

FIG. 1b is a diagram of an alternative display device which may be used with the invention;

FIG. 2 is a schematic block diagram of a second embodiment of the present invention;

FIG. 3 is a schematic block diagram of a third embodiment of the present invention;

FIG. 4 is a schematic block diagram of a fourth embodiment of the present invention; and

FIG. 5 is a waveform diagram illustrating various waveforms which appear in the circuits of the other figures.

among the illustrated embodiments, the circuits in FIGS. 1a and 1b indicate an exponent in the form of the position of a comma and in the form of a digit, respectively; the circuit in FIG. 2 indicates an exponent in the form of the number of commas; the circuit in FIG. 3 indicates an exponent under the condition in which a decimal point is fixed to the uppermost place; and the circuit in FIG. 4 indicates round numbers under the condition in which an exponent is fixed to "8" (signifying $\times 10^8$) and a decimal point is made floating.

PREFERRED EMBODIMENTS OF THE INVENTION

FIG. 1a illustrates an embodiment of the exponent indicating system according to the present invention.

Referring to the figure, RG_d designates a decimal point register which stores the position of the decimal point of a set number or a calculated result. The decimal point register RG_d has a memory capacity in excess of the effective calculation or indication places. For example, assuming the number of effective calculation or indication places to be eight, the memory capacity of the decimal point register RG_d may correspond to six-

teen places. In order to facilitate the explanation, the anterior 8-place stage portion of the register RG_d is represented as a register RG_1 , while the posterior 8-place stage portion is represented as a register RG_2 . The register RG_2 of the posterior stage portion is one added anew for the indication of an exponent. This mechanism will be clearly understood from the explanation of the operation as given hereinbelow.

A 2-input AND gate AG_{10} receives at one of its inputs 10 a decimal point signal stored in the register RG_d and at the other input a timing pulse T_L , as shown in FIG. 5. The gate AG_{10} judges whether the decimal point indication or the exponent indication is to be made.

A 2-input AND gate AG_{11} receives at one of its inputs 15 the decimal point signal and at the other input the output signal of the AND gate AG_{10} . A 2-input AND gate AG_{12} receives at one of its inputs the decimal point signal and at the other input the output signal of the AND gate AG_{10} applied through an inverter IN. The gates 20 AG_{11} and AG_{12} are employed as control gates which effect the changeover between the decimal point indication and the exponent indication in conformity with the contents of the register RG_d .

A display device DP_1 is made of display tubes, light emitting diodes or the like. Each of eight positions of the display DP_1 is provided with numeral indicating segments S_1-S_7 generally forming the shape of the figure 8, a decimal point indicating segment S_d , and a comma indicating segment S_c for indicating the exponent. The electrodes of these indicating segments have one side thereof commonly connected to a corresponding one of the position driver terminals P_1-P_8 in each position. On the other side, the electrodes are commonly connected to respective segment driver terminals for each of corresponding segments of the eight positions. Among the segment driver terminals, only a decimal point segment-driving terminal P_d and a comma segment-driving terminal P_c are illustrated in the drawing. The position driver terminals P_1-P_8 are respectively connected to receive switching signals (digit signals) DT_1-DT_8 , as shown in FIG. 5.

A decimal point driver circuit DR_d drives the decimal point segments S_d in accordance with the decimal point signal which has been received from the AND gate AG_{12} . Accordingly, the output terminal of the driver circuit DR_d is connected to the decimal point driver terminal P_d . A comma driver circuit DR_c drives the comma segments S_c in response to the decimal point signal received from the AND gate AG_{11} . Therefore, the output terminal of the driver circuit DR_c is connected to the comma driver terminal P_c .

The operation of the indicating circuit thus constructed will now be described.

When a number is set or a calculated result is requested, a decimal point signal representative of the position of the decimal point of the number is fed to the foremost stage portion of the register RG_d , and is circulatively stored within the register RG_d . Contents to be stored in the register RG_d differ as below, in dependence on whether the integral part of the number falls within eight places or lies beyond eight places. In order to facilitate the explanation, the contents of the decimal point register RG_d will be expressed hereunder throughout the description of any embodiment by reading out successively from the uppermost place the states of the respective places within a reference time immediately before the timing pulse T_L shifts from the

lower level (logic "0") to the upper level (logic "1"), namely, within a time in which the relation of $\bar{T}_L \cdot DT_s (=T_H \cdot DT_s) = 1$ holds among the timing pulse T_L , the digit signal DT_s , a bit signal BT_s , and a clock pulse ϕ_2 , as shown in FIG. 5.

When the integral part is covered within eight places, a predetermined place of the register RG_1 of the anterior stage portion becomes "1", and all the places of the register RG_2 of the posterior stage portion become "0". By way of example, for a number 1234.5678, the contents of the decimal point register RG_d become "00010000 00000000."

When the integral part exceeds eight places, all the places of the register RG_1 of the anterior stage portion become "0", and a predetermined place of the register RG_2 of the posterior stage portion becomes "1". By way of example, for a number 33333333123, the contents of the decimal point register RG_d become "0000000000100000." In summary, the binary signal "1" representing the decimal point appears in the anterior stage register RG_1 for a number whose integral part lies within eight places, while the signal "1" moves rightwards and appears in the posterior stage register RG_2 for a number whose integral part lies beyond eight places. In the latter case, the number of upper eight places is stored in the effective indication places of a numeral register (not shown) for storing numeral parts.

The AND gate AG_{10} detects by the use of the timing pulse T_L , which of the anterior and posterior stage registers the binary signal "1" representative of the decimal point is contained in. In more detail, if the binary signal "1" is in the register RG_2 of the posterior stage portion, it will be delivered from the register RG_d to the AND gate AG_{10} in a period in which the timing pulse T_L is "1". On the other hand, if it is in the register RG_1 of the anterior stage portion, it will be delivered to the AND gate AG_{10} only during a period in which the timing pulse T_L is "0". For this reason, when the output of the AND gate AG_{10} becomes "1", it is an indication that the binary signal representing the decimal point is included in the register RG_2 of the posterior stage portion, namely, that the integral part of the set number has more than eight places. In contrast, when the output of the AND gate AG_{10} is "0", it is an indication that the integral part of the number lies within eight places.

Whether the decimal point signal stored in the register RG_d is to be fed to the decimal point driver circuit DR_d or to the comma driver circuit DR_c is determined on the basis of the detecting result of the AND gate AG_{10} . This distribution or changeover is executed by the AND gates AG_{11} and AG_{12} . More specifically, in the case where the integral part exceeds the number of effective indication places, that is, where the output of the AND gate AG_{10} is "1", the AND gate AG_{11} is enabled and the decimal point signal is fed to the comma driver circuit DR_c for exponent indication. In case where it falls within the effective indication places, that is, where the output of the AND gate AG_{10} is "0", the AND gate AG_{12} is enabled and the decimal point signal is fed to the decimal point driver circuit DR_d .

For example, in the case where the integral part of a number has eleven places (33333333123) exceeding the eight effective indication places by three places, the contents of the decimal point register RG_d become "00000000 00100000." The decimal point signal delivered from the register RG_d (in this case, synchronized with the digit signal DT_5) is fed to the comma driver

circuit DR_c , to light the comma indicating segment S_c , which is in the third place as determined from the uppermost place (in the fifth place as determined from the lowermost place) and having the digit signal DT_5 applied to the electrodes on one side. The approximate figures of the number are indicated as "33333333" in the display DP_1 . Also in the case where the integral part consists of three places, the decimal point signal synchronized with the digit pulse DT_5 is delivered from the decimal point register RG_d . However, it is fed to the decimal point driver circuit DR_d by the AND gate AG_{12} . In this case, the decimal point segment S_d in the fifth place is lit.

With the display device DP_1 in FIG. 1a, in the case where the integral part exceeds the effective indication places by n places, the exponent indication is performed in such a way that the comma indicating segment in the n -th place, as determined from the uppermost one, is lit. In order to make the reading easier, the comma indicating segments S_c may be replaced with separate numerical indicating elements which are located in the respective places, as illustrated in FIG. 1b. In this case, when the indication is, for example, "43678245," it is read as expressing 43678245×10^3 .

FIG. 2 shows another embodiment of the exponent indicating circuit according to the present invention.

The exponent indicating circuit in FIG. 2 is constructed by adding OR gates OG_2 – OG_8 , AND gates AG_1 – AG_8 and registers RG_3 and RG_4 to the exponent indicating circuit in FIG. 1a. It is a circuit for indicating an exponent in the form of a number of commas. That is, in accordance with the exponent indicating circuit in FIG. 2, the exponent n of the round numbers $A \times 10^n$ is indicated by lighting n commas.

Referring to the figure, the i -th OR gate OG_i receives as its inputs the output signals of all of the flip-flop circuits from the lowermost place FF_1 to the i -th place FF_i among the flip-flop circuits FF_1 – FF_8 , which constitute the decimal point register of the posterior stage RG_2 .

For example, the fifth OR gate OG_5 receives the output signals of the flip-flop circuits FF_1 – FF_5 as its inputs.

The AND gates AG_1 – AG_8 are employed as control gates which control the timing for supplying the output signals of the OR gates OG_1 – OG_8 . To control the input terminals of the AND gates, there is applied a timing pulse $T_H \cdot DT_s$ which is the logical product between the timing pulse T_H and the digit signal DT_s . When a decimal point signal of sixteen places is just loaded in the decimal point register RG_d , the AND gates AG_1 – AG_8 are enabled.

The registers RG_3 and RG_4 store signals fed from the AND gates AG_1 – AG_8 . The output signal of a flip-flop circuit FF_{21} in the lowermost place of the register RG_4 is fed to the comma segment driver circuit DR_c , shown in FIG. 1a. The output signal of the flip-flop circuit FF_1 in the lowermost place of the register RG_2 is fed to the decimal point segment driver circuit DR_d through the AND gate AG_{12} which is controlled by the timing pulse T_H .

The posterior stage of the register RG_4 is fed back to the anterior stage of the register RG_3 through an AND gate AG_{13} . The opening and closing of the feedback loop is controlled by the timing pulse T_L . When the feedback loop is opened, that is, when the timing pulse T_L becomes "0" to disable the AND gate AG_{13} , the contents of the register RG_3 are cleared. The registers RG_3 and RG_4 can also be used as registers for arithme-

tic control, for example, registers for controlling the progress of multiplication and division. In this case, the AND gates AG₁–AG₈ may be disabled during the calculations. In the embodiment, the two registers RG₃ and RG₄ are connected in cascade, and thus the duty d of the indication is enhanced ($d=1/8$). In the case where a reduction of the number of circuit elements is more preferable even at some sacrifice of the duty d ($d=1/16$), only the register RG₃ may be employed in a manner to circulate its contents by means of the AND gate AG₁₃.

Description will now be made of the operation of the exponent indicating circuit thus constructed.

The AND gate AG₁₂ effects essentially the same operation as that of the AND gate AG₁₂ in FIG. 1. If the binary signal "1" is contained in the decimal point register of the anterior stage portion RG₁ (when the integral part is covered within eight places), it will be supplied from the register RG₂ to the AND gate AG₁₂ at the level "1" of the timing pulse T_H. Since the AND gate AG₁₂ is in the enabled state at this time, the binary signal "1" subsequently passes through the AND gate AG₁₂ and is supplied to the decimal point driver circuit DR_d. On the other hand, if the binary signal "1" is contained in the decimal point register of the posterior stage portion RG₂ (in the case where the integral part of the number has more than eight places), it will be supplied from the register RG₂ to the AND gate AG₁₂ at the level "1" of the timing pulse T_L, namely, at the level "0" of the timing pulse T_H. Since, however, the AND gate AG₁₂ is in the disabled state at this time, the binary signal "1" cannot pass through the AND gate AG₁₂ and is not fed to the decimal point driver circuit DR_d.

In summary, the AND gate AG₁₂ functions to pass the decimal point signal for the integral part within eight places, and to block the decimal point signal for the integral part over eight places. In the former case, a predetermined decimal point segment S_d is lit. In the latter case, no decimal point segment S_d is lit.

The i -th OR gate OG_i detects when any one of the outputs of the flip-flop circuits of the first to i -th places FF₁ to FF_i becomes "1". In other words, when the output of the flip-flop circuit of the i -th place FF_i becomes "1", the outputs of OR gates OG_i to OG₈ become "1". The output signals of flip-flop FF₁ and the OR gates OG₂–OG₈ are controlled by the AND gates AG₁–AG₈, and are fed to the flip-flop circuits FF₂₉–FF₃₆ in parallel. The timing at which the AND gates AG₁–AG₈ are enabled corresponds to the time at which the timing pulse T_HDT₈ becomes "1". Accordingly, only when the integral part of the number exceeds eight figures is the signal "1" fed to some of the flip-flop circuits FF₂₉–FF₃₆. By way of example, for the integral part of a twelve-figure number (345678443213) which exceeds eight figures by four places, the contents of the decimal point register RG_d become "00000000 00010000". Then, the signal "1" is fed to the four flip-flop circuits FF₂₉–FF₃₂. That is, the contents of the register RG₃ become "00001111" from the uppermost place (from FF₃₆). The signal is fed to the comma driver circuit DR_c. Thus, the 12-figure number is indicated as "34567844", which can be read as expressing approximate figures 34567844×10^4 . In this way, the exponent 4 is indicated in such a manner that commas in the lower places are lit.

If the contents of the register RG₃ are circulated in the opposite direction, the twelve-figure number will be indicated as "34567844". Unlike the case of the circuit in FIG. 2, the exponent 4 is indicated in such manner that commas in the upper places are lit.

FIG. 3 shows a further embodiment according to which the exponent indicating circuit in FIG. 1 is somewhat modified. Herein, an exponent is indicated by one of the exponent indicating elements (8)–(15) which are disposed above the respective numeral segments forming the shape of the figure 8. When the exponent indication is performed, the position of the decimal point is fixed to the uppermost place.

Differences in the exponent indicating circuit in FIG. 15 3 from that in FIG. 1 principally relate to the additional provision of set preference RS flip-flop circuits FF₄₀ and FF₄₁, and AND gate AG₁₄, and an OR gate OG₁₀, and that the display elements (8)–(15) are employed instead of the comma indicating segments S_c as the exponent indicating elements.

The set preference RS flip-flop circuit FF₄₀ in FIG. 3 is a delay type flip-flop circuit whose writing operation is conducted by a clock pulse ϕ_1 shown in FIG. 5 and whose reading operation is conducted by the clock pulse ϕ_2 . The set input terminal S of the flip-flop circuit FF₄₀ is connected to receive the output signal of the AND gate AG₁₀, namely, the signal indicating if the integral part exceeds eight places of the effective indication places. The delay type set preference RS flip-flop circuit FF₄₁, whose writing operation is conducted by a timing pulse (word pulse) W_p shown in FIG. 5, has its set input terminal S connected to an output terminal Q of the flip-flop circuit FF₄₀. The flip-flop circuits FF₄₀ and FF₄₁ are adapted to be reset by the word pulse W_p. 35 Although detailed explanation of the operation is omitted, these flip-flop circuits store the output signal of the AND gate AG₁₀ for fixed periods of time (the period of the pulses ϕ_1 as to FF₄₀, the period of the pulses W_p as to FF₄₁) on the basis of the standard truth tables of the 40 set preference flip-flop circuits. That is, the flip-flop circuits FF₄₀ and FF₄₁ store an indication if the integral part exceeds the effective indication places. In case where the effective indication places are exceeded, an output "1" is provided, whereas in the case where they are not exceeded, an output "0" is provided.

One of input terminals of the AND gate AG₁₄ is connected to receive the digit signal DT₈ for lighting the decimal point in the eighth place under the fixed state, while the other control input terminal is connected to 50 receive the output signal of the flip-flop circuit FF₄₁. To the inputs of the OR gate OG₁₀, there are applied the digit signal DT₈ (fixed point lighting signal) received after the control by the AND gate AG₁₄ and a floating point lighting signal received after the control by the AND gate AG₁₂. An output signal of the OR gate OG₁₀ is fed to the decimal point driver circuit DR_d.

A display device DP₃ is provided with the exponent indicating segments (8)–(15) as previously stated. These 60 exponent indicating segments are successively driven from the lowermost place by the digit signals DT₁–DT₈.

The exponent indicating circuit operates as described below.

In the case where the integral part of the number falls within eight places forming the effective indication places, the output of the flip-flop circuit FF₄₁ is always "0", and hence the AND gate AG₁₄ is held disabled. As a consequence, similarly to the circuit in FIG. 1, the

circuit in FIG. 3 effects only a decimal point indication and does not effect an exponent indication.

In the case where the number of figures of the integral part exceeds the number of effective indication places, the output of the flip-flop circuit FF_{41} is always "1". The AND gate AG_{12} is therefore kept disabled, so that the floating point signal is not fed from the decimal point register RG_d to the decimal point driver circuit DR_d . On the other hand, the AND gate AG_{14} is enabled, so that the fixed point signal DT_8 passes through the AND gate AG_{14} and the OR gate OG_{10} , to be fed to the decimal point driver circuit DR_d . Thus, the decimal point segment in the uppermost place (the eighth place) is fixedly lit. Further, the AND gate AG_{11} is also enabled, so that the decimal point signal passes through the AND gate AG_{11} , to be fed to an exponent driver circuit DR_i . Thus, a predetermined exponent indicating element is lit. In this manner, in the case where the integral part exceeds the effective indication places by m places, the m -th exponent indicating element as determined from the uppermost place is lit as in FIG. 1. By

way of example, a number 45678324283 is indicated as "4.5678324", and the indication is read as expressing the round number 4.5678324×10^10 .

FIG. 4 illustrates a still further embodiment of the exponent indicating circuit according to the present invention. With this embodiment, in the case where the integral part exceeds the number of effective indication places, the indication is made with the fixed exponent 8. In correspondence with the number of excessive places, the decimal point moves.

The construction of the exponent indicating circuit in FIG. 4 differs from that of the embodiment in FIG. 3, in the following points:

1. An indicating element ' $\times 10^8$ ' is provided. A pin P_9 connected to electrodes of the indicating element on one side is connected to receive a DC voltage or a timing pulse such as a digit signal.

2. In order to raise the indication duty of the decimal point segments, the decimal point signal is derived from both a decimal point register of the anterior stage RG_1' and a decimal point register of the posterior stage RG_2' , and is fed to the decimal point driver circuit DR_d .

3. The number of places of each of the decimal point registers RG_1' and RG_2' is increased by 2 for detection of an overflow, counting fraction over $\frac{1}{2}$ as one and disregarding the rest, and so forth. Consequently, in the case where the number of places of the integral part is greater than eight, which forms the number of effective indication places (in the case where the exponent indication is performed), the decimal point signal is supplied from the third place of each register to the decimal point driver circuit DR_d . For the same reason, the number of the digit signals differing in phase from one another is increased from 8 to 10 though no illustration is made.

The operation of this exponent indicating circuit will now be explained.

When the integral part is covered within eight places forming the effective indication places, the output of the flip-flop circuit FF_{41} is always "0", and hence, the exponent driver circuit DR_i does not operate and the indicating element ' $\times 10^8$ ' is not lit. The AND gate AG_{11} is enabled, while the AND gate AG_{12} is disabled. Therefore, the decimal point signal is delivered only from the lowermost places of the anterior and posterior stage registers through the OR gate OG_{11} , AND gate AG_{11}

and OR gate OG_{13} to the decimal point driver circuit DR_d . Thus, a predetermined decimal point segment is lit.

In the case where the integral part has more places than the effective indication places, the output of the flip-flop circuit FF_{41} is always "1". Hence, the exponent driver circuit DR_i operates to light the indicating element ' $\times 10^8$ '. At this time the AND gate AG_{11} is disabled, while the AND gate AG_{12} is enabled. Therefore, the decimal point signal is delivered from the third places (as reckoned from the lowermost place) of the anterior and posterior stage registers through the OR gate OG_{12} , AND gate AG_{12} and OR gate OG_{13} to the decimal point driver circuit DR_d . Thus, a predetermined decimal point segment is lit in correspondence with the number of places in excess of the number of effective indication places. It will be understood that the indication duty d of the decimal point segments is $1/10$ in this case (without the OR gates OG_{11} and OG_{12} , $d=1/20$).

As stated above, the position at which the decimal point signal is derived from each register is changed-over between the lowermost place and the third place as reckoned from the lower-most place in dependence on whether or not the integral part exceeds the effective indication places. The reason for the changeover will be more definitely understood from the following description.

The changeover is ascribable to the fact that, since the two additional places are provided for the detection of an overflow, etc., in each of the anterior and posterior stage-decimal point registers, the position of the decimal point shifts leftwards in the case where the number of places of the integral part is over the number of effective indication places. More specifically, if the decimal point signal is always derived from the lowermost place of each register, the contents of the decimal point register RG_d will become "000000001000000000" for the integral part of eight places. The decimal point segment in the first place is thus lit, so that no trouble arises. However, for the integral part exceeding eight places, by way of example, for a number 333333333333 greater than the eight places by

four places, the contents of the decimal point register RG_d becomes "0000000000001000000". Since the signal "1" is present in the seventh place as reckoned from the lowermost place, the decimal point signal synchronized with the digit signal DT_7 appears in the lowest place of the register RG_2' or RG_1' . Eventually, the decimal point segment in the second place as reckoned from the uppermost one is lit, to indicate the number as 33.333333×10^8 which is smaller by two places than actually should be. Therefore, the decimal point signal in the case of performing the exponent indication is derived two places previously in the embodiment. Accordingly, in the case where the decimal point register RG_d is employed as the memory register for only the decimal point and the exponent as in the embodiments of FIGS. 1-3, the OR gate OG_{12} , inverter IN_1 , AND gates AG_{11} and AG_{12} and OR gate OG_{13} can be dispensed within the exponent indicating circuit in FIG. 4.

As described above, in accordance with the present invention, the capacity (the number of memory places) of the decimal point register is made larger than the number of effective calculation places or the number of effective indication places, and the exponent indica-

tion is effected by utilizing the increased places. It is therefore possible that a number whose number of places is greater than the number of effective indication places or the number of effective calculation places can be indicated in approximate figures.

Although the present invention has been described in connection with the preferred embodiments, it can adopt various modified means without being restricted thereto.

For example, an exponent indicating circuit may be constructed by combining the embodiments in FIGS. 1 to 4. For example, the indication duty can be raised in such way that the OR gate OG₁₁, etc., in the circuit of FIG. 4 are added to the circuits of FIGS. 1 and 3.

Although, in the embodiments, the decimal point signal not coded is stored in the decimal point register RG_d, the same object can be similarly accomplished when a decimal point signal coded into binary signals of 1, 2, 4, 8 .... is stored in the register. In this case, accessory circuits, such as a decoder circuit, are required, but the capacity of the whole decimal point register can be reduced. Needless to say, the present invention is also applicable to the display device of a printer, etc.

What is claimed is:

1. An exponent indicating system for use with a numerical display device having a plurality of display positions, a decimal point indicator element for each position and an exponent indicator element, said system comprising a decimal point shift register having a number of stages which exceeds the number of display positions of said display device for storing the position of a decimal point of a number, an exponent indicator driver circuit connected to said exponent indicator element, first means connected to the output of said register for detecting the relative position of said decimal point with respect to the number of display positions in said display device, and second means connected to said register and said first gating means for actuating said exponent indicator driver circuit in dependence on the position of said decimal point in said number.

2. An exponent indicating system as defined in claim 1, wherein said first means includes a first AND gate having one input connected to the output of said register and clock means for applying a periodic clock pulse to a second input of said AND gate, said clock pulse having a duration equal to the shifting time of a number of stages of said register equal to the number of display positions of said display device.

3. An exponent indicating system as defined in claim 2, wherein said second means includes a second AND gate having one input connected to the output of said register and a second input connected to the output of said first AND gate, the output of said second AND gate being connected to said exponent indicator driver circuit.

4. An exponent indicating system as defined in claim 3, further including a decimal point driver circuit connected to said decimal point indicator elements, and wherein said second means further includes a third AND gate having one input connected to the output of said register and an inverter circuit connecting the output of said first AND gate to a second input of said third AND gate, the output of said third AND gate being connected to said decimal point driver circuit.

5. An exponent indicating system as defined in claim 3, wherein said shift register has a number of stages

equal to twice the number of display positions of said display device.

6. An exponent indicating system as defined in claim 3, wherein said first means further includes first and second flip-flops connected in tandem between the output of said first AND gate and the input to said second AND gate.

7. An exponent indicating system as defined in claim 6, further including a decimal point driver circuit connected to said decimal point indicator elements, and wherein said second means further includes a third AND gate having one input connected to the output of said register and an inverter circuit connecting the output of said second flip-flop to a second input of said third AND gate, the output of said third AND gate being connected to said decimal point driver circuit.

8. An exponent indicating system as defined in claim 7, wherein said second means further includes a fourth AND gate having one input connected to the output of said second flip-flop and a second input receiving a timing pulse, and an OR gate having inputs connected to the outputs of said third and fourth AND gates and an output connected to said decimal point driver circuit.

9. An exponent indicating system for use with a numerical display device having a plurality of display positions, a decimal point indicator element for each position and an exponent indicator element, said system comprising a decimal point shift register having a number of stages which exceeds the number of display positions of said display device for storing the position of a decimal point of a number, an exponent indicator driver circuit connected to said exponent indicator element, first means connected to the output of said register for detecting the relative position of said decimal point with respect to the number of display positions in said display device, second means connected to said register for actuating said exponent indicator driver circuit in dependence on the position of said decimal point in said number, and a decimal point driver circuit responsive to said first means for actuating said decimal point indicator elements.

10. An exponent indicating system as defined in claim 9, wherein said shift register comprises first and second shift register portions connected in tandem and each portion having a number of stages equal to the number of display positions of said display device.

11. An exponent indicating system as defined in claim 10, wherein said second means includes a second shift register corresponding to the decimal point shift register, a plurality of OR gates corresponding to the respective stages of said second shift register portion and each having inputs connected to the respective outputs of each stage of said second shift register portion of equal or lower order, and a plurality of AND gates connecting the outputs of the respective OR gates to the inputs to respective stages of said second shift register, the output of said second shift register being connected to said exponent indicator driver circuit.

12. An exponent indicating system as defined in claim 9, wherein said second means includes a first AND gate having one input connected to the output of said register and clock means for applying a periodic clock pulse to a second input of said AND gate, said clock pulse having a duration equal to the shifting time of a number of stages of said register equal to the number of display positions of said display device.

13. An exponent indicating system as defined in claim 12, wherein said second means includes first and second flip-flops connected in tandem between output of said first AND gate and said exponent indicator driver circuit.

14. An exponent indicating system as defined in claim 13, wherein said shift register is made up of first and second shift register portions connected in tandem and each having a number of stages exceeding the number of display positions of said display device.

15. An exponent indicating system as defined in claim 14, wherein said first means includes a first OR gate having inputs connected to the respective outputs of said shift register positions and means connecting the output of said first OR gate to said decimal point driver circuit.

16. An exponent indicating system as defined in claim 14, wherein said first means further includes a first OR gate having inputs connected to the respective outputs of said shift register portions, a second OR gate having respective inputs connected to intermediate points of said first and second shift register portions, second and third AND gates having first inputs connected respectively to the outputs of said first and second OR gates, inverter means for applying to a second input of said first OR gate the inverted output of said second flip-flop, a second input of said second OR gate being connected directly to the output of said second flip-flop, and a third OR gate receiving the outputs of said second and third AND gates and having its output connected to said decimal point driver circuit.
